UNITED STATES PATENT OFFICE.

ALBERT G. EVERSON, OF WILMINGTON, DELAWARE.

PITCHER'S TARGET.

1,043,308.

Specification of Letters Patent.

Patented Nov. 5, 1912.

Application filed February 27, 1912. Serial No. 680,281.

To all whom it may concern:

Be it known that I, ALBERT G. EVERSON, of Wilmington, in the county of Newcastle and State of Delaware, have invented certain new and useful Improvements in Pitcher's Targets; and I do hereby declare the following to be a full, clear, and exact description of the invention, such as will enable others skilled in the art to which it applies to make and use the same.

The primary object of this invention is to provide a target for the practice of baseball pitchers, and so arranged that all balls properly delivered, and which would, in a game, count as "strikes" are separately returned from those balls imperfectly pitched or delivered and which count as "balls"; and a further object is to separately record the number of perfect and imperfect balls as they are returned to the pitcher, thereby enabling him to keep an accurate record of his practice work.

The invention will be hereinafter fully set forth and particularly pointed out in the claims.

In the accompanying drawings, Figure 1 is a view in perspective. Fig. 2 is an enlarged front elevation, with parts broken away and parts in section. Fig. 3 is a horizontal sectional view.

Referring to the drawings, 1 designates a sheet, preferably of canvas, and rectangular in outline. This sheet may be supported by any suitable means, that shown consisting of a frame 2 of piping. In its center this sheet has an oblong vertically extending opening 3, the length of which corresponds to the distance between the knee and shoulder of a man of ordinary height, while its width corresponds to that of the "home" plate. Back of this opening 3 is a pocket 4, also of canvas, which is secured to the main sheet at its side and bottom edges. Its bottom 5 is inclined forwardly and to one side of the opening where it opens into a trough 6 on the back of the sheet. The lower end of this trough terminates at an opening in the sheet so as to discharge the balls delivered through opening 3 into an inclined way 7 which extends forward from the target sufficiently far to return the balls to the pitcher. Extending across the face of the sheet, beneath the opening 3, is a second trough 8 which is inclined in opposite direc-

tions from the two side edges of the sheet, 55 the two branches of the trough meeting at a point to one side of opening 3. From their point of meeting these two branches of the inclined trough open into a second inclined way 9 by which all imperfectly pitched balls 60 are returned to the pitcher.

On each of the inclined return ways I locate any suitable registering device, as conventionally indicated at 10, and having each a trip 12 which extends into the paths of 65 travel of the balls, whereby an accurate record may be kept of all balls thrown, regardless of whether they are perfectly or imperfectly delivered.

By means of my invention an exceedingly 70 simple device is obtained for the exercise and improvement of baseball pitchers, who are thereby enabled to practise without the assistance of another person, and at the same time they may preserve an accurate record 75 of the work performed.

I claim as my invention:

1. A target of the character described consisting of a sheet having a vertical opening, a pocket in rear of said opening, a trough 80 leading from said pocket, a second trough to receive balls striking the sheet outside of the opening, and separate ways extending forwardly from the target and leading from each of the troughs.

2. A target of the character described consisting of a sheet of flexible material having a vertical opening, a pocket of flexible material in rear of said opening, a trough in rear of the sheet leading from said pocket, 90 a second trough in front of the sheet and extending transversely thereof, and separate ways extending forwardly from the sheet and leading from each of the troughs.

3. A target of the character described consisting of a sheet having a vertical opening, a pocket in rear of said opening, a trough leading from said pocket, a second trough to receive balls striking the sheet outside of the opening, separate ways extending forwardly 100 from the target and leading from each of the troughs, and registering devices having actuating members in said ways.

4. A target of the character described consisting of a flexible sheet having a vertical 105 opening, a pocket in rear of said opening, the bottom of said pocket being inclined forwardly and to one side, a trough at the rear

of the sheet leading from said pocket, a second trough extending transversely of the sheet beneath the opening and inclined from the opposite side edges thereof, separate return ways leading from said troughs, and registering means connected to said troughs.

In testimony whereof, I have signed this

specification in the presence of two subscribing witnesses.

ALBERT G. EVERSON.
